UNITED STATES PATENT OFFICE.

RUSSELL SEWELL, OF CEDARTOWN, GEORGIA.

CASE FOR TOOTH-BRUSHES.

No. 901,841.

Specification of Letters Patent.

Patented Oct. 20, 1908.

Application filed March 13, 1908. Serial No. 430,819.

To all whom it may concern:

Be it known that I, RUSSELL SEWELL, a citizen of the United States, residing at Cedartown, in the county of Polk and State of Georgia, have invented a new and useful Case for Tooth-Brushes, of which the following is a specification.

This invention relates to a case or holder for tooth brushes and has for its object to provide a comparatively simple and inexpensive device of this character adapted to receive and house a tooth brush so that the latter may be conveniently carried in the pocket without danger of soiling the clothes or liability of the brush bristles becoming filled with dust, dirt and other foreign matter.

A further object of the invention is to provide a case or holder having a series of perforations formed in one end thereof to permit the circulation of air around and between the brush bristles and thus render the latter dry and sanitary.

A still further object of the invention is generally to improve this class of devices so as to increase their utility, durability and efficiency as well as to reduce the cost of manufacture.

Further objects and advantages will appear in the following description, it being understood that various changes in form, proportions and minor details of construction may be resorted to within the scope of the appended claims.

In the accompanying drawings forming a part of this specification: Figure 1 is a perspective view of a case or holder for tooth brushes constructed in accordance with my invention. Fig. 2 is a longitudinal sectional view of the same. Fig. 3 is a top plan view. Fig. 4 is a detail longitudinal sectional view illustrating a modified form of the invention.

Similar numerals of reference indicate corresponding parts in all of the figures of the drawings.

The improved holder forming the subject matter of the present invention comprises an elongated casing or housing 5 formed of aluminum or other suitable material and provided with an interior chamber or a compartment 6 for the reception of a tooth brush 7.

One end of the casing 5 is provided with a transverse row of perforations 8 while the walls of the casing at the opposite end thereof are stamped or pressed laterally to produce a circumferential stop bead 9 defining a

vertical flange or extension 10 for engagement with a cap or cover 11.

The cover 11 is secured to the body of the casing by a hinge 12 preferably in the form of a spring plate, an intermediate portion of which is bowed laterally to accommodate the rib 9 while the opposite ends thereof are riveted or otherwise rigidly secured to the cover and casing, respectively, so that when the cover 11 is moved to open position and then released, the spring action of the plate 12 will automatically return the cover to closed position.

One side of the casing at the ventilated end thereof is provided with a longitudinal row 70 of perforations 13 which form a continuation of the perforations 8 so as to permit the free circulation of air around and between the bristles of the brush thereby to render the latter dry and sanitary.

The longitudinal edges of the casing at the corners thereof are preferably curved or rounded at 14 so as to prevent the case from catching on any obstruction when inserting the case within or removing said case from the pocket, the beveled or rounded corners 14 also serving to reinforce and strengthen the case and give the latter a neat attractive appearance.

The opposite longitudinal edges of the cap or cover 11 are preferably inclined in the direction of the top thereof to form co-acting bearing faces 15 by means of which the cap may be conveniently grasped with the forefinger and thumb of the hand when it is desired to open the cap and remove the brush from the case.

The front wall of the cover is preferably stamped or otherwise formed with an inwardly extending lug 16 adapted to enter a corresponding socket or depression 17 formed in the flange 10 when the cap is in closed position thereby to prevent accidental opening movement of the same.

Attention is here called to the fact that the perforations 13 extend approximately one-third of the length of the casing and are disposed parallel with the longitudinal axis of the casing so that the air passing through said perforations will come in contact with the bristles of the brush and thence pass downward and out through the perforated bottom of the casing. It will thus be seen that the holder not only serves to effectually house the tooth brush and prevent the bris-

gles thereof from becoming filled with dirt and other foreign matter when carrying the brush in the pocket but by reason of the disposition of the perforations 8 and 13 the 5 brush bristles are maintained in a dry sanitary condition.

In Fig. 4 of the drawings there is illustrated a modified form of the invention in which the opposite side walls of the casing or 10 housing are formed with perforations 13' so as to permit the circulation of air transversely through the brush receiving compartment.

It will of course be understood that the 15 holders may be made in different sizes and shapes and plated, japanned or otherwise coated to give the same a neat finish.

From the foregoing description it will be seen that there is provided an extremely 20 simple, inexpensive and efficient device admirably adapted for the attainment of the ends in view.

Having thus described the invention what is claimed is:

25 1. A tooth brush holder comprising an elongated casing having one end thereof open and provided with a circumferential stop bead defining a vertical flange, a cap forming

a closure for the open end of the casing and adapted to engage the flange, and a spring 30 plate having its intermediate portion bowed laterally to accommodate the stop bead and its opposite ends rigidly connected with the casing and cap, respectively.

2. A tooth brush holder comprising a casing having one end thereof open and provided with a circumferential stop bead defining a vertical flange, a cap forming a closure for the open end of the casing, a spring plate having its intermediate portion bowed 35 laterally to accommodate the bead and its opposite ends rigidly secured to the casing and cap, respectively, the opposite sides of the cap being beveled in the direction of the top thereof to form bearing surfaces, there being a 40 depression formed in the flange and adapted to receive a lug carried by the cap for locking the latter in closed position.

In testimony that I claim the foregoing as my own, I have hereto affixed my signature 45 in the presence of two witnesses.

RUSSELL SEWELL.
